TOM THORNYCROFT, OF WESTMINSTER, ENGLAND, ASSIGNOR TO JOHN I. THORNYCROFT & CO., LIMITED, OF WESTMINSTER, ENGLAND.

INTERNAL-COMBUSTION ENGINE.

1,308,562.

Specification of Letters Patent.

Patented July 1, 1919.

Application filed August 24, 1916. Serial No. 116,750.

To all whom it may concern:

Be it known that I, TOM THORNYCROFT, a subject of the King of Great Britain and Ireland, residing at Westminster, England, have invented Improvements in or Relating to Internal-Combustion Engines, of which the following is a specification.

This invention relates to internal combustion engines, more particularly of the two stroke cycle type, supplied with oil as fuel, and it has for its object to effect certain improvements directed to the securing of more effective engine control. For this purpose it includes the employment of air under pressure for periodic admission, at will, to the engine cylinder in order not so much to expel products of combustion as to promote before or during the stroke preceding the working stroke circulation of the gases contained in the combustion chamber and thus to insure the gases in the neighborhood of the ignition plug being rendered sufficiently active to give rapidity of ignition and enable a small super-compression to be obtained so that the power of the engine can be controlled. The said air (hereinafter called the controlling air) may be conducted to the bulbs, vaporizers or cylinder heads, and is selectively supplied at will to the chest of an air distributing valve and thence periodically admitted to the engine either as high pressure air for starting, or as lower pressure air for power control at desired points of the engine cycle.

The scavenging properly so called which is effected regularly is or may be effected by air compressed in the crank case beneath the engine piston and admitted by the air port in the usual and well known manner of two cycle internal combustion engines.

The invention is more especially associated with engines adapted to be started with air derived from a high pressure source of supply under the control of a rotary or other distributing valve or valves and while the admission of air to the cylinder for the purposes of the invention may be effected with the aid of a separate and similar rotary or other suitable valve arrangement, a feature of the improvements consists in the provision of a compact and self contained valve mechanism such that by manipulation of a single handle the air for all purposes required can be controlled. Such a valve mechanism is adapted to be connected to

the engine through a suitable check valve arrangement so that it is not affected by high cylinder pressures and can remain inoperative when its use is not desired.

The air for engine control purposes according to the invention may be derived from the same source as for starting but since this is or may not be necessary and it is common to employ multi-stage air compressors, it is convenient in such circumstances to arrange for the said valve mechanism to cut out the higher pressure portion of the compressor and employ the lower pressure portion to supply the scavenging or like air, thereby lessening the load upon the engine.

But in order that the invention may be more readily understood it will be further described with reference to a multicylinder reversible marine engine with which is combined a two stage air compressor having a cut out valve between the high pressure stage and the receiver of the low pressure stage, it being understood that the compressor when in full operation is adapted to charge reservoirs or so-called bottles for the storage of air for starting purposes.

According to this example, high and low pressure air outlet valves and the compressor control valve are selectively opened by cam mechanism under the control of a hand wheel capable of one complete revolution or part of a revolution only, suitable gearing at the same time adjusting the position of a pivoted seating for a constantly driven rotary distributing valve. Such a hand wheel has five principal working positions which may be termed "starting ahead", "starting astern", "running ahead with controlling air", "running astern with controlling air" and "compressing air into the bottles for starting purposes". The last described position is effective when the engine is running in either direction.

Midway between the above mentioned positions are four neutral positions in any one of which the hand wheel may be left without influencing the engine in any way. Any suitable indexing means may be employed to retain the hand wheel in correct position.

In the accompanying drawings, Figure 1 is a diagrammatic view of such an arrangement. Fig. 2 is a central vertical section of the controlling mechanism of this arrangement. Fig. 3 is a section corresponding to

the line A—B of Fig. 2. Fig. 4 is a face view of a portion of Fig. 2 removed.

In Fig. 1, *a* represent four engine cylinders each having a head *b* fitted with a non-return valve *c*. Each of these valves *c* is connected by piping *e* to an air distributor *d*. *f* is the low pressure air receiver of a two-stage compressor; *g* a relief valve therefor; *h* is the high pressure air receiver; *i* a sleeve 10 valve for cutting out the high pressure stage of the compressor and *j* a spring against the action of which the valve *i* requires to be moved to put the said high pressure stage into action again.

k are two air bottles connected together and to the air controller *d* and high pressure air receiver *h* of the compressor by piping *l*. *m* is a high pressure air relief valve and *n* is the piping connecting the low pressure air 20 receiver *f* to the distributor *d*.

In the constructional form of air distributor shown in Figs. 2, 3 and 4, the hand wheel *o* is secured to a shaft *p* inclined to the axis of the rotary distributing valve shaft *r* 25 and geared to the adjustable seating *s* for the valve *t* through bevel pinions *u*. The seating *s* is provided with four equidistantly spaced ports (two of which are shown at *v*) communicating respectively with four annular spaces *w* disposed axially along a cylindrical body extension *x* of the valve seating *s* and in constant register with ports *y* connected by the piping *e* and check valves *c* of Fig. 1 to the cylinder heads *b*.

The distributing valve *t* which is of conical formation is provided with a single port *z* and with a rectangular projecting part *1* adapted to engage a slot *2* at one end of the shaft *r* for driving it continuously from the engine, which shaft extends into the extension *x* of the valve seating. The bearings for the hand wheel shaft *p* are provided in a body *3*, forming part of the distributing valve air chest *4*, and in a cover *5* for such body *3*. The body *3* carries a pair of spring-loaded mushroom valves *6* and *7*, one of which, namely *6*, controls a passage *8* between the distributing valve air chest *4* and the stationary air bottle arrangement *k* 40 (Fig. 1) and the other of which, namely *7*, controls a passage *9* between the air chest *4* and the receiver *f* of the low pressure stage of the compressor (Fig. 1). These air inlet valves *6* and *7* may, as shown, be disposed 45 at opposite sides of the hand wheel shaft *p* in a plane that contains the axis of the latter but out of alignment with each other so that a pair of axially displaced edge cams 10 and 11 upon the said hand wheel shaft can cooperate with the valve spindles 12 and 13.

The contours and angular relationship of these cams will be readily ascertained from Fig. 3. By this means each valve *6* and *7* can be held open at will in both the ahead 60 or the astern operation. A third edge cam

14 on the hand wheel spindle *p*, may produce angular movement of an arm 15 connected to the compressor cut out valve *i* by any suitable lever and linkage system such as the rod *16* and arms *17*, *17^a* and *18* (Fig. 1). 70 The cam 14 is effective to permit the valve *i* to close under the action of its spring *j* each time that either the air inlet valve *6* or *7* is opened. The hand wheel *o* may be held by means of a trigger arrangement comprising 75 a catch *19* coöperating with a notched disk *20* and moved into and out of engagement therewith by a handle *21* upon the said hand wheel, the said handle being actuated in one direction by a spring *22* and by hand pressure in opposition thereto. *23* is a stop upon the cover *5* with which a stop *24* upon the hand wheel *o* is adapted to engage with rotation in opposite directions. The cover *5* is provided with a dial *25* the wording 80 upon which although not identical with the phraseology employed at the commencement hereof will sufficiently indicate the results that obtain with the positions marked. The notches numbered *26* indicate the remaining 85 pair of neutral positions referred to in which the hand wheel *o* may be left without influencing the engine in any way. In all the figures the parts are in position corresponding to bottle charging. 90

The operations of starting, stopping, putting into operation the controlling air, or compressing air into bottles ready for restarting in either direction, are made as follows:—

To start ahead.—The hand wheel *o* is rotated to the ahead starting position, and the high pressure air derived from the bottles *k* is allowed to flow to the cylinder *a* which happens to be in the proper position in the cycle of operations, due to registration of the port *y* connected to that cylinder with the port *z* of the distributing valve *t*, after which the remaining cylinders receive air in proper rotation and exhaust as ordinarily. 100

When the engine has thus been started by air, the fuel is supplied separately and the engine run explosively. If full power is at once required, the hand wheel *o* is then rotated to the ahead scavenging position, that 105 is to say, to the position marked "extra air ahead" in Fig. 4, and low pressure air admitted through the valve *7* is injected at a suitable time in the cycle to effectually remove the exhaust gases. This insures that 110 the oil is readily and promptly ignited upon injection. As an alternative, if full power is not required, the hand wheel *o* can be at once turned to one of the two neutral positions, marked "Running either way" and 115 numbered *26* respectively.

Starting in the astern direction is accomplished in exactly the same way, by revolving the wheel to the astern position after stopping the engine by cutting out the fuel 120

supply, or in other suitable ways. After starting the engine in either direction the air pressure in the bottles *k* can be restored by moving the hand wheel *o* to the pumping 5 position marked "air compressor" in Fig. 4 in which position air is compressed and pumped into the starting bottles. At this latter time the valve *i* between the high and low pressure stages *h* and *f* of the 10 compressor is simultaneously opened by the action of the cam 14 against the action of the spring *j* and both the air inlet valves 6 and 7 are maintained closed by the action of their springs 27.

15 As will be seen from Fig. 2 the high pressure air supply tends to keep the valve 6 closed while the low pressure air supply tends to open the valve 7. The pressure of each spring 27 is slightly in excess of the 20 low pressure air supply so that air entering the air chest 4 will be unable at any time to open the valve 6 and escape past it.

What I claim is:—

1. For starting and controlling a two 25 stroke internal combustion engine, sources of air under different pressures, a valve chest, manually controlled means adapted to admit air at will from either of said sources to said valve chest, and means driven by the 30 engine adapted to periodically admit air from said valve chest to the engine cylinder.

2. For starting and controlling a two 35 stroke internal combustion engine, sources of air under different pressures, a valve chest, manually controlled means adapted to admit air at either of said pressures at will to said valve chest, and means driven by the engine adapted to periodically admit 40 said air from said valve chest to the engine cylinder at a period in the cycle preceding the working stroke.

3. In an internal combustion engine, engine-driven means for compressing air to two different pressures, a valve chest, manually 45 controlled means adapted to admit such air to said valve chest, and means driven by the engine for the admission of air from said valve chest to the engine cylinder at a higher pressure for starting purposes 50 and at a lower pressure after the engine is working explosively.

4. In an internal combustion engine, a 55 multi-stage compressor, a valve adapted to cut the higher pressure stage out of use, means for the periodic admission of air derived from the higher pressure stage section of the compressor to the engine cylinder for starting purposes, means for the periodic admission of air from the lower pressure 60 stage section of the compressor to the engine after the same is working explosively and means adapted to close the valve between the compression stages during both high and low pressure air admission, as aforesaid.

65 5. In an internal combustion engine, the

combination with an engine cylinder arrangement of an adjustable ported valve seat and seat extension through which air can pass to the cylinder arrangement, sources of air at two different pressures, an air distributing valve working on said seating and controlling the ports therein, hand controlled means for adjusting the position of said seating and extension, an air chest enclosing said valve and seating and hand controlled means for selectively admitting at will to said air chest air under higher or under lower pressure. 70 75

6. In an internal combustion engine, a constantly driven rotary air distributing 80 valve, a rotatably adjustable valve seating therefor, hand operating means for rotating the said valve seating, a high pressure air inlet valve, a low pressure air inlet valve, such valves being adapted to alternatively 85 supply high and low pressure air to said distributing valve, and cam mechanism controlled by the hand operating means referred to, adapted at one time to open the low pressure air valve alone and at another time to 90 open the high pressure air valve alone.

7. In an internal combustion engine, a constantly driven rotary air distributing 95 valve, a rotatably adjustable valve seating therefor, hand operating means for rotating the said valve seating, a high pressure air reservoir, a multistage compressor adapted to charge said reservoir, a valve adapted to cut the higher pressure stage out of use, a high pressure air inlet valve, a low pressure 100 air inlet valve, such valves being associated with the rotary distributing valve, and cam mechanism controlled by the hand operating means referred to, adapted at one time to open the low pressure air valve and close the 105 compressor cut out valve, at another time to open the high pressure air valve and close the said cut out valve and at yet another time to permit of opening of the compressor 110 cut-out valve alone.

8. In an internal combustion engine, a rotary air distributing valve, a low pressure air inlet valve tending to open automatically under such air pressure, a high pressure air inlet valve tending to remain closed under 115 such air pressure, both the said valves being adapted to conduct air to the distributing valve, spring means loading both valves in excess of the low pressure air supply and cam mechanism adapted to alternatively 120 open the said valves in opposition to the spring load.

9. In an internal combustion engine, a rotary air distributing valve, a high pressure source of air, a low pressure source of air, 125 valves separately controlling admission of such air to the distributing valve, a spring preponderating over the low pressure air source opposing opening of the corresponding valve to admit air to the distributing 130

valve and a similar spring opposing opening of the high pressure air admission valve due to air admitted to the distributing valve by the low pressure air valve.

- 5 10. In an internal combustion engine, the combination with a rotary air distributing valve embodying a rotatably adjustable seating, of a shaft and gearing for adjusting such seating, a hand wheel on said shaft, a 10 high pressure air inlet valve at one side of the shaft, a low pressure air inlet valve at the opposite side of such shaft, the said valves being out of alinement, and a pair of cams axially displaced along the said shaft, 15 adapted to alternatively open the air inlet valves.

11. In an internal combustion engine, the combination with a plurality of engine cylinders, of an adjustable valve seat and seat 20 extension having ports and passages therein for connection with the respective cylinders, a rotary air distributing valve constantly working on said seating to control the ports therein, means for rotatably adjusting the 25 position of said seating relatively to said valve, an air chest inclosing said valve and seating and means for admitting air under pressure to said air chest.

12. In an internal combustion engine, the 30 combination with a multiple-cylinder engine arrangement of a rotatably adjustable valve seat having ports that respectively communicate with the cylinders, hand operated means for rotating said valve seat, an air 35 distributing valve that is continuously rotatable and is furnished with a port that, as the valve rotates, is successively brought into juxtaposition with each port of the valve seat, sources of air at two different pressures, 40 hand controlled means for alternatively admitting air from such sources to said rotary distributing valve, and a non-return valve arrangement between the distributing valve and the cylinder arrangement.

45 13. In an internal combustion engine, the combination with a multi-stage compressor and an engine cylinder arrangement, of a rotary air distributing valve, a reservoir adapted to be charged from the high pressure stage of the compressor, means adapted

to alternatively admit air from the reservoir and low pressure stage of the compressor to the distributing valve, means adapted to cut the high pressure stage of the compressor out of action while air is being admitted to the 55 rotary valve as aforesaid and a non-return valve arrangement between the distributing valve and the cylinder arrangement.

14. In an internal combustion engine for the purpose of alternatively admitting air 60 from the low pressure stage of a compressor and a reservoir charged from the high pressure stage, with a cutting out of the said high pressure stage except when the reservoir is to be charged, the combination with an air chest of a rotatably adjustable ported valve seating, a ported casing therefor, a plurality of engine cylinders, connections between said cylinders and the ports in said casing, non-return valves in such connections, a rotary ported valve associated with the valve seating and driven continuously by the engine, a shaft inclined to the axis of the rotary valve, gearing between such shaft and valve seating, high and low pressure, air 75 inlet valves, controlling passages communicating with the air chest referred to, a multistage compressor, a valve adapted to cut the higher pressure stage out of use, a member adapted to be moved to close the compressor cut-out valve, cams upon the inclined shaft coöperating with such member and with the high and low pressure air inlet valves, a hand wheel upon the shaft, and indexing means adapted to hold the shaft in 80 positions where the high and low pressure air inlet valves are alternatively opened to start and scavenge the engine respectively in both forward and reverse driving, holding the compressor cut-out valve closed, and 85 also to hold the shaft in a position where the member referred to is permitted by its cam to open the cut-out valve and permit the reservoir to be charged.

Signed at Winchester, in England, this 95
25th day of June, 1916.

TOM THORNYCROFT.
